UNITED STATES PATENT OFFICE.

ABRAHAM SCHOPF, OF PHILADELPHIA, PENNSYLVANIA, ASSIGNOR TO AMERICAN CARAMEL COMPANY, OF YORK, PENNSYLVANIA, A CORPORATION OF PENNSYLVANIA.

DESIGN FOR A CHOCOLATE DROP.

40,615.

Specification for Design.

Patented Apr. 5, 1910.

Application filed January 24, 1910. Serial No. 539,908. Term of patent 7 years.

To all whom it may concern:

Be it known that I, ABRAHAM SCHOPF, a citizen of the United States, residing in the city and county of Philadelphia, State of Pennsylvania, have invented a new, original, and ornamental Design for Chocolate Drops, of which the following is a specification, reference being had to the accompanying drawing, forming part thereof.

Figure 1 represents a perspective view of a chocolate drop showing my new design. Fig. 2 represents an end view thereof.

I claim:

The ornamental design for a chocolate drop as shown.

ABRAHAM SCHOPF.
